UNITED STATES PATENT OFFICE

HARRY W. JONES, OF WEBSTER GROVES, MISSOURI, ASSIGNOR TO SANFORD INVESTMENT COMPANY, OF WILMINGTON, DELAWARE, A CORPORATION OF DELAWARE

RAILWAY CAR END STRUCTURE

Application filed February 25, 1930. Serial No. 431,153.

This invention relates to the frame end structures of mine and similar cars. Usually such cars have side members and end members forming a frame. The end members are usually rigidly joined to the side members and, in some cases, have associated with them other elements, whereby an end structure is formed. In the present case, the elements thus associated with the end member are a bumper and coupling means, including a coupling pin or similar element.

The object of the invention is to combine with the end structure means for supporting the coupling pin to allow horizontal movement of the pin on the end member of the car frame against yielding resistance.

In the form shown by the drawings, the frame end member which constitutes the major or principal element of the end structure is the major element in the car frame end structure disclosed by Letters Patent of the United States, No. 1,486,547, granted to Hugh W. Sanford, March 11, 1924; that element being composed of an upright web or back and horizontal flanges directed away from the side members, the end member having its ends attached to the side sills by means of angle members which are joined to said web and to the webs of the side sills.

In the forms of end structure herein described there is combined with the main element a horizontally slidable member which supports the coupling pin. With the slidable member is associated a spring or a plurality of springs which yieldingly resist movement away from the body of the car when a link surrounding the coupling pin is under strain away from the car and parallel to the length of the car. Thereby the coupling pin is permitted to move horizontally away from the body of the car and independently of the main end structure element. The range of such movement of the coupling pin is limited, as will appear further on.

In the form illustrated by the drawings, said horizontally slidable member extends rearward of the web of the major or principal end structure member and a part of said slid- 50 able member extends above the major mem-

ber and another part extends through said web into the space between said flanges.

In the accompanying drawings,

Fig. 1 is a plan of my improved end structure applied to the ends of the side sills of 55 a car, said sills and end structures forming the car frame;

Fig. 2 is a front elevation of the structure shown by Fig. 1;

Fig. 3 is a side elevation looking at the 60 structure of Figs. 1 and 2 from the left;

Fig. 4 is an upright section on the line, 4—4, of Figs. 1 and 2, looking in the direction of the arrows;

Fig. 5 is a horizontal section on the line, 65 5—5, of Figs. 2 and 4;

Fig. 6 is a transverse upright section on the line, 6—6, of Fig. 4, looking toward the right;

Fig. 7 is a perspective of one of the corner members used for joining the side sills to the 70 end structure;

Fig. 8 is a horizontal section on the line, 8—8, of Fig. 4;

Fig. 9 is an upright transverse section on the line, 9—9, of Fig. 4, looking toward the 75 left, the lower part of the coupling pin being broken away and dotted, and the cushioning wood being omitted;

Fig. 10 is a section similar to Fig. 5, but including only the lower part of the coupling 80 pin yoke and the adjacent walls, and showing two springs instead of the one spring of Figs. 4 and 5.

Referring to said drawings, A, A are the ends of side sills of suitable form. In the 85 drawings these sills are of channel-form with flanges, A1, directed outward.

B is the principal or major member of the car end structure. This has the upright web, B1 (presenting a flat back face toward the 90 body of the car) and an upper horizontal flange, B2, and a lower horizontal flange, B3, both of said flanges being directed away from the body of the car. Said flanges are rigid on the web, B1. The drawings show said 95 flanges integral with said web; but they may be of separate pieces rigidly secured to the web by riveting or similar means. The corners of the flange, B2, are cut to make slanting edges, B4; and the corners of the flange, B3,

are similarly cut to make slanting edges, B5.

In the form shown in the drawings, said major member, B, is long enough to partially overlap the adjacent ends of the side sills. Said member and the side sills are joined to each other by means of corner angle members, C. One of these angle members is shown in perspective in Fig. 7 of the drawings. One arm or blade of the angle member rests against the flat back face of the web, B1, of the major member, B, and is secured to said member by bolts or rivets, C1, extending through said blade and the web, B1. The other arm or blade of the angle member extends into the space between the flanges, A1, of the adjacent side sills and bears against the outer face of the upright web of the side sill. Bolts or rivets, C2, extend through said blade and said web to join said parts to each other. In the form shown in the drawings, nine such bolts or rivets, C2, are used for each blade. These corner angle members and the bolts or rivets used for securing these angle members to the member, B, and the side sills, A, are to be sufficiently strong to give rigidity to the frame. The web B1, of the member, B, is high enough to allow making a coupling link space above the bumper, as will be described further on.

The upper web, B2, has an elongated hole, B6, to receive the coupling pin or bolt, F; and the lower flange, B3, has an elongated hole, B7, to receive the coupling pin or bolt. Both of said holes are on the same upright axis and are elongated in the direction of the length of the car. Normally the coupling pin or bolt is held in the rear part of said openings.

An inner or second member, D, of strong wood, preferably oak, is placed on the lower flange, B3, and against the upright web, B1, of the major member, B. The upper and the lower and the inner faces of the wood member, D, are straight, while the outward face of said wood member nearly conforms to the outer edges of the flanges, B2 and B3, and the major member, B, the middle part of the wood member being extended outward a little beyond said flanges to meet the bumper, E.

Midway between the ends of the major member, B, an angle-form anchor plate, D1, extends across the upper face of the wood member, D, and downward between said member and the web, B1, of the major member, B, and is secured to said web by rivets, D2. (Figs. 4 and 9). The horizontal part of the anchor member has an elongated hole, D3, to receive the coupling pin or bolt, F, to be described further on, the elongation being in the direction of the length of the car. Said anchor plate is only of sufficient width to receive said coupling pin and be strong enough to assist in supporting said coupling pin.

A bumper, E, is curved and of channel-

form having an upright web, E1, and an upper flange, E2, and a lower flange, E3. Said bumper member is placed at the middle of the end structure and has its web, E1, bearing against the outer, upright face of the wood member, D, while its upper flange, E2, overlaps the upper face of the lower member of the yoke, as will be described further on. The lower flange, E3, of the bumper extends slidably across the lower face of the lower flange, B3, of the major member, B. This bumper member is to receive contact or impact from the bumper of another car. The bumper member and the outer part of the wood member form a bumper, the wood being a cushioning member or material against which the bumper member rests. Space for a coupling link is to be left between the flange, E2, of the bumper member and the upper flange, B2, of the major end structure member, B. The upper flange E2 has an elongated aperture E4 and the lower flange E3 has an elongated aperture E5, those apertures being on the axial line of the apertures or holes B6 and B7 and are adapted to receive the coupling-pin which is to be received by the holes or apertures B6 and B7 and the elongated hole D3 in the anchor plate D1. In addition to allowing limited movement of the coupling-pin toward and from the car body, the elongated holes, E4 and E5, allow limited movement of the bumper toward the body of the car. When the wood cushioning member, D, is compressed or is absent, such movement being arrested by contact with the coupling-pin when that pin is at its limit toward the body of the car. Furthermore, the coupling pin limits movement of the bumper away from the major member. And the enlarged apertures in the bumper, together with the other enlarged apertures, normally allow the coupling-pin to move horizontally without disturbing the bumper. Thus the coupling-pin is operatively related to the bumper and the major member. Also, by contact and through the coupling-pin, the bumper is operatively related to the major member and the major member flanges are thus a part of the coupling means. Thus the bumper is operatively associated with the coupling pin—dependent upon said pin, controlled by said pin, and said pin is controlled by the other coupling members.

A feature of practical value is to be noted. Normally the spring or springs, G11, will function to retard the outward movement of the coupling-pin F; but if the spring or springs become broken or displaced, the functioning of the coupling-pin and the coupling link will not be destroyed. Outward strain on the coupling link will draw the coupling-pin in the same direction until the limit of the elongated apertures, above described, has been reached. Then the coupling-pin will be held as would be the case

if the yoke and the spring or springs were absent. Thus failure of the spring or springs will not disable the coupling structure.

On the upper face of the upper flange, B2, of the member, B, is placed a reinforcing plate, F1. Said plate extends from the plane of the rear or back face of the web, B1, to the front or outer edge of the flange, B2, and said plate, F1, is wide enough to receive an elongated hole, F2, through which the coupling pin extends, the elongation being in the direction of the length of the car, and wide enough to extend laterally beyond each side edge of the upper arm, G2, of the yoke, G, described further on. The plate, F1, is secured to the flange, B2, by means of bolts or rivets, F3. (Figs. 1, 2, 6 and 9.)

A reinforcing plate, B8, is applied to the upper part of the back face of the web, B1, and is a little wider than the width of the upper arm, G2, of the yoke, G, and extends downward to the plane of the upper face of the anchor member, D1, and extends upward above the plane of the upper face of the reinforcing plate, F1, and is suitably secured to the web, B1, by means of bolts or rivets. (Figs. 1, 3, 4, 5, 6 and 10). B9 is one such rivet. This extends horizontally through the web, B1, and the reinforcing plate, B8, and a frusto-conical sleeve, B10. One head of said rivet engages the outer face of the web, B1, and the other head engages the sleeve, B10. Thereby said parts are firmly bound to each other. The rivet, B9, is in the upright longitudinal middle plane of the car and in a line extending approximately midway between the bumper flange, B2, and the upper flange, B2, of the major member, B.

The coupling pin, F, is carried by the plate metal yoke, G. This is composed of an upright web, G1, and an upper horizontal arm, G2, and a lower horizontal arm, G3. The arm, G2, lies flatwise on the reinforcing plate, F1, and in a notch, G4, in the upper end of the reinforcing plate, B8. The lower arm, G3, extends through a notch, G5, in the lower edge of the reinforcing plate, B8, and through a horizontal slot, B11, in the upright web, B1, and thence slidably between the anchor member, D1, and the flange, E2, of the bumper, E. The arm, G2, has a hole, G6, fitting around the upper part of the coupling pin, F, to prevent sidewise movement, in any direction, of said pin relative to the yoke arm. The lower arm, G3, has a hole, G7, for similarly receiving and holding the middle part of the coupling pin, F.

It has already been described that the reinforcing plate, F1, and the upper flange, B2, of the major member, B, and the upper flange, E2, of the bumper and the anchor plate, D1, and the lower arm, B3, of the major member, B, and the lower arm, E3, of the bumper have elongated openings or holes through which the coupling pin, F, extends, and

wherein the coupling pin may have movement toward and from the body of the car. It will now be seen that longitudinal movement of the yoke, G, will carry the coupling pin horizontally back and forth parallel to the length of the car as far as permitted by said elongated holes. While said elongated holes permit movement of the coupling pin parallel to the length of the car, they prevent sidewise movement of the coupling pin. This is one means of holding the yoke to movement parallel to the length of the car. The engagement of the upper arm, G2, of the yoke in the notch, G4, and the engagement of the lower arm, G3, in the notch, G5, constitute another means for so guiding the yoke.

On the face of the web, G1, of the yoke which is directed toward the web, B1, of the major element or member, is a reinforcing plate, G8. A rivet, G9, in alignment with the rivet, B9, extends through the web, G1, and the reinforcing plate, G8, and a frusto-conical sleeve, G10, and binds said three members to each other. That sleeve, G10, and the sleeve, B10, on the rivet, B9, constitute seats for the ends of an expanding coil spring, G11. Said spring constantly tends to push the yoke, G, away from the major member or element, B, and toward the opposite end of the car. Thus said spring and the yoke tend to hold the coupling pin, F, toward the web, B1, of the element or member, B. A coupling link, H, is located between the upper bumper flange, E2, and the upper flange, B2, of the major element, B, and surrounds the coupling pin. When said link is in engagement with another car and strain is put on said link with sufficient force to compress the spring, G11, the yoke, G, is moved toward or away from the web, B1, until the pin, F, reaches the limit in said elongated holes. As soon as the strain on the link, H, diminishes or ceases, the spring, G11, again expands and returns the yoke, G, and the coupling pin, F, to normal position. As will now be understood, the function of the yoke, G, and the spring, G11, is to cause gradual or progressive applying of strain through the link, H. This yoke and spring function when two adjacent cars tend to separate from each other. The bumper, E, is to function when two cars are in contact with each other or are driven against each other.

Now it will be observed that this end structure constitutes a part of the car frame and also includes bumper means and a yielding coupling means. And it will be seen that the several members of this end structure are interrelated and inter-dependent and co-operative.

In Fig. 10, two springs, G11, and two sets of rivets, G9 and B9, are shown.

It is to be noted that, while my improved end structure is applicable to mine cars of various sizes, its features are especially needed

in large mine cars, strains being larger in such cars.

I claim as my invention,

1. In a car frame end structure, the combination of a major element adapted to have its ends joined to the side members of the frame and having an upright web and horizontal flanges directed away from the body of the frame and said flanges being apertured 10 on an upright axis for receiving a coupling-pin and permitting limited movement of said pin in the direction of the length of said frame, a coupling-pin supporting yoke having an arm extending slidably through said web and having another arm extending above the upper of said flanges and said arms having apertures in alignment with said flange apertures, and a spring in engagement with said web and said yoke for yieldingly resisting movement of said yoke away from the car frame.

2. In a car end structure, the combination of relatively stationary members including a horizontal flanged bumper, said members 25 having on an upright line apertures large enough to receive a coupling pin and permit limited movement of said pin in the direction of the length of the car, means transverse to the end structure and extending rearward 30 of the major element of the end structure and movable in the direction of the length of the car and apertured to receive the coupling pin, and yielding means located between said rearward extension and the rear of the major 35 element and acting to normally move said movable means toward the body of the car and thereby hold the coupling pin at its limit toward the body of the car.

3. In a car frame end structure, the combination of a major element adapted to have its ends joined to the side members of the frame and apertured for receiving a coupling-pin and guiding and limiting movement of said pin in the direction of the length 40 of said frame, coupling-pin supporting means transverse to and extending rearward of said major element and movable transversely to said major element and being apertured in upright alignment with the major element 45 apertures for receiving and carrying a coupling-pin, and yielding means at the rear of the major element and in operative relation with said supporting means for yieldingly resisting movement of said supporting means 50 away from the body of said frame.

4. In a car frame end structure, the combination of a transverse metal means having an upright wall and upper and lower horizontal flanges directed away from the car, a 60 bump resisting and cushioning means resting on the lower of said horizontal flanges, a flanged metal bumper member having an upright bumping face and having the flanged part directed toward the car frame and overlapping at least a part of said cushioning 65

means and the flanged part of said bumper member and the flanges of the transverse metal means being apertured on a common upright axis to receive a coupling pin and larger in the direction of the length of the car than the diameter of a coupling pin, a coupling pin supporting means having two spaced-apart horizontal arms above the cushioning means and approximately parallel to the length of the car and said arms being 70 apertured for a coupling pin on the same upright axis as the first mentioned apertures, a coupling pin through all said apertures, and spring means positioned for yieldingly resisting movement of the coupling pin supporting means away from the car.

5. In a car frame end structure, the combination of a transverse horizontal major element of channel-shape having an upright web and upper and lower horizontal flanges directed away from the car frame, a horizontal bumper member having upper and lower horizontal flanges directed toward the car frame, the lower bumper member flange overlapping the lower major element flange and the upper bumper member flange extending into this space between said major element flanges the said major element flanges and said bumper member flanges being apertured on an upright axis to receive a coupling pin 95 said apertures being larger in the direction of the length of the car than the diameter of the coupling pin, a coupling pin supporting member having two arms approximately parallel to the flanges of said major element, 100 the arms of said supporting member being apertured on the same axial line as the first mentioned axial line to receive a coupling pin, a coupling pin through all said apertures, and spring means positioned for yieldingly 105 resisting movement of the coupling pin supporting means away from the car.

In testimony whereof I have signed my name, this 18th day of February, in the year one thousand nine hundred and thirty.

HARRY W. JONES.
